UNITED STATES PATENT OFFICE.

ERNEST D. TERRY, OF NEW YORK, N. Y., ASSIGNOR TO PHOENIX GLASS COMPANY, OF PITTSBURG, PENNSYLVANIA, A CORPORATION OF WEST VIRGINIA.

DESIGN FOR A LAMP-SHADE.

No. 38,311.

Specification for Design.

Patented Nov. 13, 1906.

Application filed July 23, 1906. Serial No. 327,442. Term of patent 7 years.

To all whom it may concern:

Be it known that I, ERNEST D. TERRY, residing at New York, in the county of New York and State of New York, have invented a new, original, and ornamental Design for Glass Lamp-Shades, of which the following is a specification, reference being had to the accompanying drawing, which illustrates the design by a side view, showing part of the body portion of the shade in dotted lines.

The body portion of the glass shade is out-

wardly flaring and terminates in a horizontally and outwardly extending ledge. Depending from the outer edge of this ledge is a vertical curtain, as shown in the drawing.

I claim—

The ornamental design for a lamp-shade as shown and described.

ERNEST D. TERRY.
